UNITED STATES PATENT OFFICE

EDWARD CLAXTON WALTER, OF ORANGE, NEW JERSEY, ASSIGNOR TO THE ELLIOTT-FISHER COMPANY, OF NEW YORK, N. Y., A CORPORATION OF DELAWARE

TRIPLE-HINGE INDEX UNIT

Application filed April 21, 1925. Serial No. 24,773.

This invention relates to card indexes of that type characterized by a series of cards which are normally stored or nested in a card tray and adapted to be swung, individually or in series, to expose any desired card.

The object of the invention is to provide a plurality of cards with a swinging support, so arranged that while all of the cards may be nested in the tray in the usual manner, a plurality of cards may be elevated from the tray by the swinging of their supports and then individually swung to facilitate recording thereon, or the inspection of a record already made on either side of the individual cards.

To the accomplishment of the stated object, and others subordinate thereto, the preferred embodiment of the invention is illustrated in the accompanying drawings in

20 which:

Figure 1 is a longitudinal sectional view of a card tray showing a plurality of card units, one of which occupies its normal or stored position, and the other of which occupies an elevated position on a posting board.

Figure 2 is a plan view of the same.

Figure 2^a is a plan view showing a modified form of posting board.

Figure 3 is a perspective view of one of 30 the card units, and

Figure 4 is another perspective view showing the cards elevated and swung in opposite directions to horizontal positions.

A shallow tray 1 is provided at the bottom 35 of its side walls with guideways 2 for the reception of the opposite ends of retaining portions 3 of a card index unit 4, which in this instance includes two record portions, cards, or leaves 5 and 6, connected by independent hinges 7 and 8, with an intermediate portion 9, having hinge connection as at 10, with the retaining portion 3.

Usually, the leaves 5 and 6, instead of carrying the record directly, constitute card holders to which record cards 11 and 12 are detachably secured. The specific manner of attaching the cards to the holders constitutes no part of the present invention, but it 50 is usual to slit at least one of the holders

or leaves, as at 13 and 14, and to pass through these slits tabs 15 and 16, formed on the cards.

Whether or not the record is printed directly on the leaves 5 and 6, which thus constitute record cards, or on separate cards 11 and 12, carried by the leaves, is immaterial since in either event the index unit will be seen to embrace hinged record portions or cards retained in the tray by a retaining portion 3, through the medium of a hinged intermediate portion 9 which may assume either a horizontal or a vertical position, to dispose the cards in either a depressed or elevated position as shown in Figures 3 and 4, for storage or recording.

The retaining portions of the adjacent index units are overlapped in the guide in the tray to facilitate the close nesting of the units so that a large number thereof may be stored in a small space, but when it is de-

sired to enter a record a selected index unit is raised to a vertical position from the hinge 10 and a slotted posting board 17 is dropped upon the tray with the cards extended through a slot 17^a in the board. If desired, this slot may be opened at one end as shown at 17^b in Figure 2^a so that the board can be slipped laterally to its position. In any event, when the board has been located the cards can be swung down thereon, either together or individually, in either direction so that either face of either card may be inspected or posted.

From the foregoing the present invention may be clearly understood, but the right to vary or modify the same within the scope of the protection granted is expressly reserved.

What I claim is:

1. The combination with a tray, having a guide, of an index device engaging the guide and having an axis of movement adjacent said guide, said device including a plurality of record portions mounted to space them from said axis and having individual swinging movement.

2. The combination with a tray, of a posting board having an opening and an index unit mounted in the tray, and having a plurality of record portions hinged to swing

down over the posting board at opposite sides of the opening therein.

3. The combination with a tray, having a guide, of an index unit including a retaining portion engaging the guide, a plurality of hinged record portions, an intermediate portion carrying the record portions, and hinged to the retaining portion of the unit, and a posting board having an opening to accommodate the intermediate portion of the index unit.

4. The combination with a tray, of an index device having means for retaining it on the tray, said device being movable to swing as a unit relative to said retaining means and tray, and including a plurality of record portions and means to mount them in spaced relation to the retaining means and with individual swinging movement.

5. The combination with a tray, having a guide, of an index device including retaining means engaging the guide, a plurality of record portions, and a portion intermediate the record portions and the retaining means, the intermediate portion being hinged to the retaining means and the record portions being hinged to the intermediate portion.

6. The combination with a tray having a guide, of a card index device including retaining means engaging the guide, a plurality of card holders, and a portion intermediate the card holders and the retaining means, the intermediate portion being hinged to the retaining means and the card holders being hinged to the intermediate portion.

7. The combination with a tray, of a posting board having an opening and adapted to rest upon said tray, and an index device including a retaining portion secured in the tray, an intermediate portion movable relative to the retaining portion to a position to allow it to project through the opening in the board, and a plurality of record portions carried by the intermediate portion and movable thereon to a position overlying the board.

8. An index device for use with a tray having a guide, said device including a guide-engaging portion, a plurality of record portions, and means connecting the record portions to said engaging portion and providing for unitary swinging movement of the record portions about an axis spaced from said engaging portion and also providing for independent swinging movement of the record portions about individual axes.

9. An index device for use with a tray and including a retaining portion for securing the device in the tray, a supporting portion hinged to the retaining portion, and a plurality of recording portions hinged at a common point to the supporting portion of said device.

10. An index device for use with a tray and including a retaining portion for securing the device in the tray, a supporting portion

hinged to the retaining portion, and a plurality of record portions spaced from the retaining portion by said supporting portion and each hinged at one edge to the supporting portion for individual swinging movement.

11. The combination with a tray and a posting board adapted to rest thereon and to be moved thereon and having an open-ended slot, of an index device including a retaining portion for retaining the device in the tray, a plurality of record portions, and an intermediate portion, the latter being hinged to the retaining portion to allow it to assume a position to be received within the slot when the posting board is moved to a suitable position on the tray.

12. In combination, an index device, a tray and a posting board supported by the tray, said index device being secured to the bottom of the tray and including a plurality of individually swinging record portions, and means movable about an axis adjacent the bottom of the tray to position the record portions in the tray for storage or above the posting board for recording operations thereon.

In testimony whereof I hereunto affix my signature.

EDWARD CLAXTON WALTER.
